(57) **CLAIM**

The ornamental design for a cruise ship, as shown and described.

DESCRIPTION

FIG. 1 is a perspective view of a cruise ship according to my new design;

FIG. 2 is a top plan view of the cruise ship shown in FIG. 1;

FIG. 3 is a side elevational view of the cruise ship shown in FIG. 1, the opposite side being a mirror image thereof;

FIG. 4 is a bottom plan view of the cruise ship shown in FIG. 1;

FIG. 5 is a front elevational view of the cruise ship shown in FIG. 1;

FIG. 6 is a rear elevational view of the cruise ship shown in FIG. 1;

FIG. 7 is a cross-sectional view of the cruise ship taken along lines 7—7 as seen in FIG. 3;

FIG. 8 is a cross-sectional view of the cruise ship taken along lines 8—8 as seen in FIG. 3;

FIG. 9 is a cross-sectional view of the cruise ship taken along lines 9—9 as seen in FIG. 3;

FIG. 10 is a partial perspective view of the rear and top of the cruise ship showing a helicopter pad; and,

FIG. 11 is a partial perspective view of the rear waterline of the cruise ship, showing a marina.
